Term of patent 14 years

(Cl. D83—1)

Fig. 4

FIGURE 1 is a front elevational view of a combined power unit and storage cabinet for an electro-therapeutic muscle-stimulator or the like embodying my new design, the contrasting surface texture of a portion of the front being indicated by stippling;

FIGURE 2 is a side elevational view thereof;

FIGURE 3 is a top plan view thereof; and

FIGURE 4 is a rear perspective view taken from the side thereof.

I claim:

The ornamental design for a combined power unit and storage cabinet for an electro-therapeutic muscle-stimulator or the like, substantially as shown.
